US00D930069S

(12) **United States Design Patent** (10) **Patent No.:** **US D930,069 S**
Stanley et al. (45) **Date of Patent:** **** Sep. 7, 2021**

(54) **PLATFORM**

(71) Applicants: **Alicia Harvey Stanley**, Gaithersburg, MD (US); **Briar D. Robinson**, Gaithersburg, MD (US); **Robert Walter Kenny, Jr.**, Mount Airy, MD (US); **Exus D. Altimus**, Manassas, VA (US); **William B. Harvey**, Laytonsville, MD (US)

(72) Inventors: **Alicia Harvey Stanley**, Gaithersburg, MD (US); **Briar D. Robinson**, Gaithersburg, MD (US); **Robert Walter Kenny, Jr.**, Mount Airy, MD (US); **Exus D. Altimus**, Manassas, VA (US); **William B. Harvey**, Laytonsville, MD (US)

(73) Assignee: **Alicia Harvey Stanley**, Gaithersburg, MD (US)

(**) Term: **15 Years**

(21) Appl. No.: **29/692,479**

(22) Filed: **May 24, 2019**

(51) LOC (13) Cl. **17-99**

(52) U.S. Cl.

USPC **D17/99**

Primary Examiner — Gino Colan

(57) **CLAIM**

The ornamental design for a platform, as shown and described.

DESCRIPTION

FIG. 1 is a front isometric view of our new design for a platform showing our new design;

FIG. 2 is a front elevational view of FIG. 1;

FIG. 3 is a back elevational view of FIG. 1;

FIG. 4 is a right side elevational view of FIG. 1;

FIG. 5 is a left side elevational of FIG. 1;

FIG. 6 is a top plan view of FIG. 1; and,

FIG. 7 is a bottom plan view of FIG. 1.

The features shown in broken lines in the drawings depict environmental subject matter only and form no part of the claimed design.

1 Claim, 5 Drawing Sheets
